PROPELLION SYSTEM

Robert D. Schultz, Whittier, Calif., assignor to Aerojet-General Corporation, Azusa, Calif., a corporation of Ohio

Filed Oct. 19, 1961, Ser. No. 146,099
12 Claims. (Cl. 60—35.3)

This invention generally relates to a thrust propulsion system suitable for use in outer space, and to an improved engine employing charged droplets of colloidal size in particular.

Prior development in the field of space propulsion has shown that devices ejecting jets of highly charged colloidal-sized droplets are an ideal means of thrust generation. As used hereinafter, a colloid shall be understood to mean a substance in a state of fine division wherein its constituent particles range in diameter from about 0.2 to about 0.005 micron. Such a charged colloid propulsion system is described in Patent application Serial No. 71,329, filed November 23, 1960 by Robert D. Schultz, Lane K. Branson, and Robert F. Chaiken, entitled "Propulsion Means," and assigned to the assignee of the present invention, now Patent No. 3,122,882. In the system described therein, the invention comprises a unique propulsion unit operable within a substantial vacuum wherein colloidal-sized electrically charged liquid particles or droplets are ejected from a point or points in contiguity with the liquid container. The charged particles are focused and accelerated through a gradient electrostatic field to produce thrust in a given direction. The ejection of colloid particles causes thrust, in accordance with the principles of classical physics, that is, for every action, there is an equal and opposite reaction. In the present device, this action reaction phenomena occurs as magnetic field interaction between the field of the colloid particles and of the accelerating rings. As the accelerating field pushes the colloid particles out one end of the chamber, the field of the colloid particles creates an equal and opposite reaction against the accelerating rings, thus pushing the chamber forward. For optimum operation of such a system liquids selected as best forming colloidal-sized particles under the conditions described have been those having a vapor pressure of 10^{-5} Hg or lower at 20° centigrade and electrical conductivity greater than 6×10^{-8} mho/centimeter but less than 10^{-5} mho/centimeter. Other desirable characteristics for the propulsion fluid are: An internal pressure greater than 7×10^9 dynes per sq. centimeter; a dielectric constant greater than 6; a density of about 1 to $1\frac{1}{2}$ grams/centimeter³; and a freezing point as low as possible, consistent with the above properties.

While the system described in this prior application provides satisfactory operation, it has been found that higher efficiency is obtained when volatile constituents are removed from the liquid, thereby eliminating corona discharge during operation. The presence of corona discharge may produce undesirable, extraneous ions in the colloid beam, the net effect of which is to waste the power of the propulsion system while contributing relatively little to the thrust. However, purification which may reduce the vapor pressure of the material to 5×10^{-6} mm. Hg or lower, while eliminating the presence of corona discharge, will also detrimentally effect the mechanism by which the electrical atomization takes place and derogates the generation of thrust. The underlying reason for the above-mentioned phenomenon has not been definitely established. Such evidence as is available, however, substantiates the explanation set forth below.

In the embodiments described in application Serial No. 71,329 an appreciable corona discharge will occur in the vicinity of the sharp ejection points of the spray bank

2

assembly at a positive potential as low as 20 kilovolts in the presence of air. The positive ions formed in the corona discharge are repelled from the positive charge tip or spray bank ejection point. The negative electrons, however, are accelerated toward the tip where they collide with the fluid particles with sufficient energy to ionize them.

This process may be described in equation form as:

where RH represents an oil molecule, $(e^-)^*$ represents an energetic electron which has been accelerated in the anode fall region of the corona surrounding the needle point, e^- is an electron after collision which is free to migrate in the oil film at the tip, and RH^+ represents a singly ionized oil molecule. It is possible to establish a field intensity at the ejection point or tip of the same magnitude as the apparent electric strength of organic liquids. As corroborated in an article describing electrical breakdown mechanism by T. J. Lewis in 27 Journal of Applied Physics, page 645 (1956), the electrons e^- condensed in the surface of the oil are capable, at field intensities easily generated by the propulsion system described, of rapidly migrating through the oil to the metal of the ejection point, where they disappear into the conduction band. This permits the heavy ions RH^+ to accumulate in the external surface of the oil covering the needle point until their mutual electrostatic repulsion (i.e., the electrostatic pressure) rises to a value sufficient to overcome the tensile strength of the oil. By tensile strength of the oil is meant intermolecular cohesion between the molecules at or below the surface of the oil film. The oil then ruptures into fairly uniform-sized colloidal droplets whose surfaces contain an appreciable number of RH^+ ions. When the ambient gas pressure is reduced to a value of 5×10^{-6} mm. Hg or less, the mean free paths of electrons and positive ions moving in the residual gas become large compared to the gap between electrodes. Under these high vacuum conditions, a self-sustained corona discharge is impossible, a negligible quantity of energetic $(e^-)^*$ electrons are available to ionize the oil molecules into RH^+ ions, and the electrical atomization process is attenuated.

Thus, in order to obtain charged liquid colloids by electrical atomization under the vacuum conditions of outer space, it will be necessary to provide charge carriers, that is, substitutes for either the $(e^-)^*$ electrons of the corona discharge or for the RH^+ particles which are produced in the liquid surface. As used herein, the term "charge carrier" is understood to mean a substance which will supply electrons capable of being accelerated from a positively charged ejection means, or which will supply positively charged particles capable of being accelerated from a negatively charged ejection means.

It is therefore the principal object of the present invention to provide a novel method of and improved means for charged colloid propulsion of a space flight vehicle.

Another object of the present invention is to provide a novel method of and improved means for improving the efficiency of a charged colloid propulsion system.

In its principal aspect, the present invention comprises a unique propulsion unit operable within an atmosphere of substantial vacuum wherein colloidal sized electrically charged particles or droplets of purified liquid are ejected from a spray bank. Means are provided for supplying charge carriers to the fluid to permit automatic charging at the particle ejection points. The charged particles are then focused and accelerated through a gradient electrostatic field to produce thrust in a given direction. Means associated with said focusing and accelerating means may be provided for neutralizing the effect of space charge on said beam of particles.

These and other objects, aspects, and features of this invention will be apparent to those skilled in the art from the following more detailed description taken together with the appended drawing, which is a schematic view of the improved propulsion system of the present invention.

As shown in the drawing, the propulsion unit comprises a spray bank 26 and associated apparatus. The spray bank 26 comprises a chamber or container 32 in which the propulsive liquid 34 is confined. This liquid is subjected to a high positive voltage by means of a circular electrode 36 which encompasses the container 32 and is connected to the first or positive power lead 20. Openings 28 on one phase of the confining chamber 32 are provided through which the liquid migrates under the influence of a force such as applied pressure or capillary attraction. The spray bank assembly 26 illustrated here comprises a first plate 50 to which are attached steel pins 52 of a small diameter, for example, approximately .030". The pins protrude through a similar pattern of holes 28 which have a diameter of approximately .003" greater than the diameter of the pins, the holes being in a second plate 54. Between the two plates 50, 54 is provided a reservoir for the fluid 34 to be dispensed. The rounded configuration of the high voltage electrode 36 is provided to prevent high voltage leakage from the sharp corners of the plates 50, 54. A high positive voltage (for positively charged colloids), shown here, or a high negative voltage (for negatively charged colloids) may be applied to the high voltage electrode 36. The high voltage is transmitted to the points of the pins 52 and a spray 40 of charged particles is produced. The fluid 34 flows from the reservoir down the pins 52, maintaining the spray 40. This flow is produced by gravity and capillary action, but could be produced by pressurizing the fluid 34 in the reservoir, in the absence of a high gravitational field. A pair of spacers 56 are provided between the plates 50, 54 to provide the proper chamber rigidity. Other types of spray banks and associated components may be used by the propulsion unit of this invention. Possible variations of the spray bank are fully disclosed in the previously mentioned copending patent application Serial No. 71,329 titled "Propulsion Means" by Robert D. Schultz, Lane K. Branson, and Robert F. Chaiken, assigned to the assignee of the present invention, now Patent No. 3,122,882.

A drift tube assembly 38 is arranged adjacent the discharge openings 28 of the confined chamber 34. The assembly 38 comprises drift tubes or accelerating rings spaced in a manner surrounding the proposed path of the charged colloidal droplets 40. The drift tube 42 furthest in distance from the spray bank 26 is connected to the negative power lead of an external power supply, not shown. The drift tube 30 closest to the spray bank 26 is connected to the positive power lead of the external power supply through a portion 44 of the voltage divider 46. It is seen that the potential gradient between the fluid 34 and the spray bank assembly 26 and the furthest drift tube 42 is provided by the presence of the voltage divider 46, the individual drift tubes achieving their potential from voltage taps intermediate the length of the voltage divider 46. By this means, an electrostatic field is provided which has a potential gradient varying from a maximum (positive) value at the spray bank 26, ground or neutral at the first drift tube 30, to a high (negative) value at the furthest drift tube 42. It is to be understood that it is fully within the scope of this invention to employ a grid arrangement rather than drift tubes, or even to employ electromagnetic focusing and acceleration.

The means employed to provide substitutes for either the $(e^-)^*$ electrons for the corona discharge or for the RH^+ ions are shown in this figure as an electron source 100 in juxtaposition to the ejection points of the spray bank which are covered with the liquid to be atomized. The electron source 100 may be, for example, a hot fila-

ment or a cold-cathode emitter. A bias of up to several hundred volts or more is necessary to accelerate the electrons from the source 100 to the dispersing tips or knife edges in order to ionize the fluid molecules. The rate of formation of RH^+ ions can be controlled by adjusting the bias voltage, by adjusting the heater current to an indirectly heated cathode, or by varying the exposed area of the electron emitter. In the embodiment shown, a variable resistance 102 is utilized to vary the bias, although the other means described could be used to accelerate the electrons from the electron source 100.

It is believed that the rate of formation of RH^+ ions will influence the size of the resulting charged liquid colloidal particles and their charge-to-mass ratio. It follows that it is possible to produce positively charged liquid colloid particles in a vacuum with a charge-to-mass ratio as high as 10^9 to 10^{10} e.s.u./g. Such charge-to-mass ratios enable reduction of the accelerating voltage required to attain a given specific impulse, and enables generation of thrust comparable to that produced by ion propulsion systems.

In the embodiment shown, a shield member 45 within which is located an electron or negative ion emitter 48 is located adjacent the rearmost accelerating drift tube or ring 42. The shield 45 is connected to be at the same high negative potential as the furthest drift tube or ring 42, and the emitter 48 is powered by a separate voltage source, not shown. It is the function of the emitter 48 to inject negative particles into the beam 40 of colloidal droplets to overcome the space-charge repulsion phenomenon, while the shield 45 insures that the negative particles are confined to the vicinity of the beam 40. The emitter 48 may, by way of example, comprise an indirectly heated cathode powered by the previously mentioned separate voltage source, or merely a hot filament, similarly powered. Other space charge neutralization means such as, for example, a rarefied neutral gas stream, may be utilized.

In operation, the purified liquid 34 having the above-described characteristics, is directed to the extremities of the dispersion means associated with the fluid reservoir 32. Several examples of fluids suitable for use in such a system are diethylphthalate, polypropylene glycol, or glycerine. Colloidal sized electrically charged particles are ejected from the spray bank 26 which is at the same high potential as the fluid reservoir. Negative charge carriers are provided to the colloid stream by the electron source 100, and the stream of particles is then focused and accelerated through a gradient electrostatic field and directed to the ambient to produce thrust in accordance with the principles of classical physics.

While the operation of a system, as explained above, is believed to be a correct explanation of the principles underlying my invention, further investigation may lead to a modification of my theory. It is to be understood, however, that the invention is independent of any theory which may be advanced to account for the results obtained. In explaining my invention, I have illustrated and described many details of construction, but it is obvious that alternatives and equivalents will occur to those skilled in the art which are within the scope and spirit of my invention. It is my desire, however, that my protection not be limited to the details herein illustrated and described, but only by the proper scope of the appended claims:

I claim:

1. A method of creating thrust in a vacuum atmosphere comprising the steps of applying an electrical potential to a body of purified liquid having a vapor pressure not greater than 10^{-5} mm. Mg about 20° centigrade and an electrical conductivity greater than 6×10^{-8} mho/centimeter but less than 10^{-5} mho/centimeter, which is confined in a means having a minute openings; directing said charged liquid to the extremities of dispersion means associated with said openings, whereby

charged liquid particles of colloidal size will be formed at said dispersion means extremities; directing negatively charged particles from an external source to said colloidal particles; ejecting said particles from said dispersion means in a beam; focusing and accelerating said beam particles; and neutralizing the effect of space charge on said beam of particles.

2. A propulsion system operable in a vacuum atmosphere comprising: a reservoir having a plurality of openings on the surface thereof; a body of fluid having a vapor pressure not greater than 10^{-5} mm. Hg at about 20° centigrade and an electrical conductivity greater than 6×10^{-8} mho/centimeter but less than 10^{-5} mho/centimeter arranged in said reservoir; fluid ejection means associated with said openings in said surface; means for applying electrical potential to said fluid body and said reservoir; negative particle emission means arranged in contiguity to said fluid ejection means; and electric focusing and accelerating means arranged in contiguity to said negative particle emission means.

3. A propulsion system as described in claim 2, and, in addition, means for space charge neutralization, said neutralization means being associated with said focusing and acceleration means.

4. A reaction propulsion system for producing thrust in a substantial vacuum comprising: a body for purified liquid having a vapor pressure not greater than 10^{-5} mm. Hg at about 20° centigrade and an electrical conductivity greater than 6×10^{-8} mho/centimeter but less than 10^{-5} mho/centimeter; means for confining said body of liquid, said confining means having minute openings through which liquid may migrate; liquid dispersion means in contiguity with said minute openings; means for subjecting said confined liquid to a relatively high electric potential; a negative particle emission source arranged in contiguity to said liquid dispersion means; means for creating and maintaining a gradient electric field in spaced relationship to said dispersion means, whereby charged colloidal-sized droplets of the liquid are ejected from said dispersion means as the result of said high potential, and are focused and accelerated in any desired direction; and means for injecting negative particles into said droplets after they have been focused and accelerated.

5. The reaction propulsion system of claim 4 wherein said liquid is selected from the group consisting of dioctylphthalate, polypropylene glycol, and glycerine.

6. A reaction propulsion system as described in claim 4 wherein said negative particle emission source comprises a cold cathode emitter.

7. A reaction propulsion system as described in claim 4 wherein said negative particle emission source comprises a hot filament.

8. A system for creating thrust in a vacuum atmosphere comprising: a reservoir having a plurality of openings on one surface thereof; a body of liquid having a vapor pressure not greater than 10^{-5} mm. Hg at about 20° centigrade and an electrical conductivity greater than 6×10^{-8} mho/centimeter but less than 10^{-5} mho/centimeter arranged in said reservoir; fluid ejection means associated with said openings in said surface; negative particle emission means externally associated with said fluid ejection means; electrostatic focusing and accelerating means arranged in contiguity to said fluid ejection means; means for applying electric potential to said liquid

body through said reservoir and said electrostatic focusing and accelerating means, a difference of potential existing between said reservoir and said electrostatic focusing and accelerating means whereby liquid particles of colloid size are ejected from said particle ejection means in a beam and said beam is focused and accelerated by said electrostatic focusing and accelerating means; and means associated with said electrostatic focusing and accelerating means for neutralizing the effect of space charge on said beam of particles.

9. A propulsion system operable in a vacuum atmosphere comprising: a reservoir having a plurality of openings in one surface thereof; a body of liquid in said reservoir, said liquid having a vapor pressure not greater than 10^{-5} mm. Hg at about 20° centigrade, an internal pressure greater than about 7×10^9 dynes per square centimeter, an electric conductivity substantially between 6×10^{-8} and 10^{-5} mho/centimeter, a dielectric constant greater than 6, and a density substantially between 1 and $1\frac{1}{2}$ grams/cm.³; fluid ejection means associated with said openings in said surface; negative particle ejection means externally associated with said fluid ejection means; electrostatic focusing and accelerating means in spaced relation with said fluid ejection means; means for applying electric potential to said liquid body, said reservoir and said focusing and accelerating means, whereby the liquid body and reservoir are at a potential of approximately 100 kilovolts of one polarity and a gradient electric field is created which varies from zero in the vicinity of said ejection means to approximately 1000 kilovolts of an opposite polarity at the position of said focusing and accelerating means furthest extended from said fluid ejection means; and means associated with said focusing and accelerating means for neutralizing the effect of space charge, said neutralization means being juxtaposed with said focusing and accelerating means which is at a potential of approximately 1000 kilovolts.

10. A reaction propulsion system as described in claim 4 wherein said negative particle emission source comprises an indirectly heated cathode.

11. A propulsion system operable in a vacuum atmosphere comprising: means for ejecting a colloidal stream of electrically charged atomized liquid droplets of colloidal dimensions, means for injecting negatively charged particles into said colloidal stream, and electric focusing and acceleration means arranged in contiguity to said colloidal particle ejection means and said negatively charged particle injection means whereby liquid particles of colloidal dimensions are ejected in a stream and said stream is focused and accelerated by said electric focusing and accelerating means.

12. A system as described in claim 11, and in addition, means for neutralizing the effect of space charge on said colloidal-sized fluid particle stream by injecting negative particles into said colloidal sized fluid particle stream after it has been focused and accelerated, said neutralizing means being associated with said electric focusing and acceleration means.
